TROLLEY WIRE SUPPORT

Samuel S. Matthes, Mansfield, Ohio, assignor to
The Ohio Brass Company, Mansfield, Ohio, a
corporation of New Jersey

Application January 16, 1940, Serial No. 314,118

17 Claims. (Cl. 191—40)

My invention relates to supports for trolley wires and particularly trolley wires on curves when employed in overhead construction for trolley bus operation.

One object of my invention is to provide a simplified construction which will be light yet strong, and which will avoid the use of a plurality of supports with their many cross wires and will permit the use of continuous trolley wires.

Other objects and benefits will be evident as I proceed with the disclosure of my invention.

My invention comprises the new and novel construction, combination and relation of parts hereinafter described and shown in the drawings accompanying this specification.

In the drawings:

Fig. 1 is a top plan view of my invention arranged for two trolley wires.

Fig. 2 is a front view in elevation of my invention.

Fig. 3 is a back view in elevation of my invention.

Fig. 4 is an enlarged top plan view of the strain plate which I employ.

Fig. 5 is a side view of Fig. 4.

Fig. 6 is a section of Fig. 4 on the line 6—6.

Fig. 7 is a section on the line 7—7 of Fig. 1.

Fig. 8 is a partial section on the line 8—8 of Fig. 1.

Fig. 9 is a side view of a trolley wire tip which I employ.

In the preferred embodiment of my invention, I provide a curved longitudinal and adjustable bar 1, preferably of flat, rectangular metal, in which one edge acts as a guide for a current collector in crossing the support. The bar is provided at each end with a clevis or other means to receive or hold a trolley wire tip 2, Fig. 9. The clevis at each end of the bar is shown as having two pair of holes, the holes of each pair registering and also registering with holes in the tip 2 to receive transverse holding means 3 to secure the bar and tips together.

Secured to the bar 1 adjacent its longitudinal center is a strain plate 4 provided with a longitudinal portion 5 and transversely disposed arms 6. The arms and intermediate portion 5 have a groove 7 therein to receive the trolley wire 8. Projecting lugs 9 and cotter pins 10 act as a safety means to prevent displacement of the wire 8. The groove 7 is curved substantially to that of the trolley wire, taking into consideration that the curvature of the wire will vary some from a normal or intermediate curvature. The arms 6

and groove 7 are shown as at or near one end of the plate 4.

The ends of the plate portion 5 are provided with holes 11 and 12 to which supporting means for the device may be attached.

The plate 4 is also provided with longitudinally aligned holes 13a, 13b, 13c, and 13d to receive the supporting stud and nut 14 of the bar 1. This stud is welded to the upper edge of the bar 1 adjacent its longitudinal center and projects through the plate 4 and may be placed in any one of the holes 13a to 13d inclusive depending upon the curvature required of the bar 1. The nut holds the stud and bar in adjusted relation 15 to the plate.

When it is desired to vary the curvature of the bar 1 during installation or after the device has been in service, or to adjust the spacing between the conductors 8, it is only necessary to position the stud and nut 14 in any one of the holes 13a to 13d inclusive which will effect a proper curvature of the bar 1 which is substantially flexible to permit bending with relative ease under manual force.

25 To prevent a flying trolley head becoming lodged between the trolley wire 8 and the bar 1, I provide deflectors 15 which are preferably flat bars of metal anchored at one end to the plate 4 and at the other end to the trolley wire by means of the clamp shown in section in Fig. 8 and comprising a grooved washer 16 and bolt and nut 17 whereby the wire 8 is clamped between the deflector 15 and washer 16. This arrangement holds the trolley wire against movement longitudinally relative to the support.

The trolley wire acts as a continuous tension rod extending between the ends of the bar 1 and, therefore, I am able to offer a simplified device which is light and strong and relatively easy to install.

40 The end tips 2 are arranged to receive the trolley wire and hold the lower edge of the bar 1 in alignment with the lower edge of the trolley wire or otherwise as may be required while the portion of the trolley wire intermediate the end tips is raised above the lower edge of the bar 1 and out of possible contact with the current collector.

To adapt my invention to support two trolley wires, as required in trolley bus operation, I connect two supports together by insulated members 18 anchored to the plates 4 by means of bolts 19 through the openings 11 and 12 respectively of the plates 4.

45 The installation of my invention comprises

supporting the plate 4 and bar 1 by means of cross span wires anchored to the plate 4 by means of the holes 11 and 12 or by other suitable means. The trolley wire is then positioned in the groove 7 and the clevis ends of the bar 1 and the cotter pins applied. The tips 2 which have open bottom grooves are then applied to the ends of the bar 1 and to the trolley wire and the tips 2' forming the groove are thus peened about the wire. The deflector bars 15 are now positioned and clamped in place on the trolley wire 8. The bar 1 may now be adjusted by positioning the stud 14 in such opening 13a to 13d inclusive as will bring the ends of the bar in substantial alignment with the trolley wire to meet the angle formed by the trolley wire. The curvature of the bar 1 should be adjusted as far as possible to bring the ends of the bar 1 and tips 2 into tangency with the trolley wire 8 at the ends of the tips 2.

The greater the curvature of the bar 1, the less the portion of the circumference of the circle covered by the bar, and vice versa, and by altering the position of the stud 14 in the openings 13 the curvature and length in degrees of the bar may be changed within the predetermined limits.

The opening 13 may be made into a single elongated slot if desired; however, I prefer the plurality of openings as shown, and the stud 14 may be rotatable or nonrotatable relative to the plate.

I do not wish to be limited to the exact details of construction shown and described for obvious modifications will occur to those skilled in the art.

I claim:

1. A trolley wire support for use on a curve in an overhead system, comprising an elongated strain plate, an elongated flexible curved bar of rectangular cross-section adapted to guide a current collector along its lower edge, means attached to the bar adjacent its longitudinal center and cooperating with the strain plate whereby the bar is attached to the strain plate, a plurality of means on the plate adapted to cooperate with the said means on the bar whereby the position of the bar may be changed along the longitudinal axis of the plate and the curvature of the bar changed whereby the ends of the bar are brought into tangency with the adjacent trolley wire, means on the plate to attach thereto supporting means for the plate, means on the plate to receive and anchor the trolley wire to the plate and means at each end of the bar to receive the trolley wire and hold it in predetermined relation to the bar.

2. A trolley wire support for use on a curve in an overhead system comprising an elongated strain plate, means associated with the plate to receive a continuous trolley wire, means to anchor the trolley wire against longitudinal movement relative to the plate, an elongated bendable bar attached to the plate in longitudinal adjustable relation to the plate, the lower edge of the bar adapted to guide a current collector, means at each end of the bar to receive and hold the trolley wire, the adjustability of the bar relative to the plate permitting the longitudinal axis of the bar at the ends of the bar and the longitudinal axis of the trolley wire to be made substantially tangent.

3. A trolley wire support for use on a curve in an overhead system comprising, a strain plate, means on the plate to receive supporting means

for the plate, means on the plate to receive a continuous trolley wire, a curved bar attached adjacent its longitudinal center to the plate in adjustable relation thereto and adapted to guide a current collector, means at each end of the bar to receive and hold the trolley wire in predetermined relation to the bar, means attached to the plate, one on each side of the plate and projecting therefrom and arranged to grip the trolley wire to prevent its longitudinal movement relative to the plate and to prevent a flying trolley pole head wedging between the bar and trolley wire after the support has been installed.

4. A portion of an overhead trolley system at a curve comprising, a strain plate, means on the plate to receive supporting means for the plate, means on the plate to receive a trolley wire, a curved bar attached to the plate adjacent the longitudinal center of the bar, means at each end of the bar to receive a trolley wire and hold it in fixed relation to the bar and a continuous trolley wire positioned in the last said means and in the said means on the plate and projecting longitudinally from the ends of the bar, the trolley wire and the plate and the bar forming triangular openings on each side of the plate and means extending between and attached to two of said parts forming the openings to reduce the area of the openings and prevent the entrance of a trolley head.

5. The combination with an elongated plate like member provided with a plurality of openings intermediate its ends and a curved yoke portion at one end to receive a trolley wire, of an elongated bar bent to a predetermined curvature and adjustable to other curvatures and having means adjacent its longitudinal center cooperating with one of said openings to secure the bar to the plate and means at the ends of the bar to attach the ends of the bar to the trolley wire, the curvature of the bar depending upon which of said openings the first said means cooperates with.

6. The combination with a trolley wire forming part of a curve of an overhead trolley system, of a strain plate with means to receive supporting means for the same, a curved seat associated with the plate to receive a portion of the trolley wire, elongated means extending longitudinally of the plate, a bendable bar to guide a current collector and provided with means cooperating with the said elongated means whereby the bar may be secured to the plate in adjustable relation thereto and means to attach the ends of the bar to the trolley wire.

7. A strain plate for a trolley wire support and pull over for use on a curve of an overhead trolley system comprising, an elongated body member of plate-like formation, means on the plate to receive supporting means for the plate, a saddle portion with a convexly grooved seat at one end of the plate to receive the trolley wire, the said seat extending in opposite directions from the longitudinal center of the plate and means intermediate the ends of the plate to receive attaching means on an elongated bendable bar in movable relation to the plate in a longitudinal direction of the plate whereby the curvature of the bar may be changed to align the ends of the bar longitudinally with the trolley wire.

8. A strain plate for use with a trolley wire on a curve of an overhead trolley system comprising, an elongated body member of plate-like formation, a saddle portion with a convex seat at one end of the plate to receive the trolley

wire, the said seat extending transversely in opposite directions from the longitudinal center of the plate and means intermediate the ends of the plate along the longitudinal center line of the plate to receive attaching means on an elongated curved bar in adjustable relation to the plate whereby the curvature of the bar may be changed to bring the ends of the bar and the adjacent trolley wire into tangency.

9. A trolley wire support for use on a curve in an overhead trolley system comprising, an elongated strain plate, means at one end of the plate to receive a continuous trolley wire, an elongated bar attached to the plate and bendable to different radii of curvature, the lower edge of the bar adapted to guide a current collector over a portion of the system, means at each end of the bar to receive and hold the trolley wire and the ends of the bar in predetermined relation and means on the plate whereby the center of the bar may be moved longitudinally of the plate and thereby change the curvature of the bar to bring the ends of the bar into tangency with the trolley wire at the ends of the bar.

10. In combination, a continuous trolley wire forming a portion of a curve of an overhead trolley system, a strain plate attached to the trolley wire, a bar bendable to different radii of curvature and adapted to guide a current collector over a portion of the system, means at each end of the bar to attach it to the trolley wire at spaced points thereon to support the ends of the bar in predetermined relation to the wire and means on the bar cooperating with means on the plate whereby the bar and plate may be secured together and the point of attachment of the bar varied relative to the plate along a line normal to the axis of the bar to adjust the curvature of the bar.

11. A support for a continuous trolley wire to support the wire at three spaced points comprising, an elongated member having means at one end to receive and support the wire at one of said points and elongated curved means of bendable material to guide a current collector there-across and having portions at each end to receive and support the trolley wire at the other two points, a third means associated with the elongated member and cooperating with one of the first two said means whereby the distance between the first two said means may be varied along the longitudinal axis of the elongated member to vary the curvature of the said curved means.

12. A trolley wire support for use in a curve in an overhead trolley system comprising an elongated plate-like member, means on the plate to receive a continuous trolley wire, a curved bar attached to the plate at a point substantially central of the bar and adapted to guide a current collector along its lower edge, the curvature of the bar being adjustable, means on the plate cooperating with means on the bar permitting adjustment of the bar longitudinally of the plate whereby the curvature of the bar may be altered, and means at each end of the bar to receive and hold that portion of the trolley wire adjacent to but beyond the bar with its lower edge in substantial alignment with the guiding edge of the bar and to hold the ends of the subtended portion of the trolley wire raised above the guiding edge of the bar whereby the current collector may pass smoothly from the wire onto the bar and vice versa.

13. A device for supporting and maintaining the separation and insulation of a pair of trolley wires forming a part of a curve of an overhead trolley construction comprising, a pair of spaced and curved flexible members, the curvature of which may be adjusted at will to meet requirements, strain means formed of a plurality of parts extending at right angles to the curved members and to which the curved members are attached, some of the parts forming the strain means constituting insulating means whereby the curved members are insulated from each other, the strain means also provided with means to which supporting means for the device may be attached, the strain means being also provided with means cooperating with means on the curved members whereby the spacing between the curved members and the curvature of the flexible members may be adjusted and the strain means and the curved members secured together after adjustment and means associated with the curved members to receive and hold the trolley wires in predetermined relation to the curved members.

14. A support for a trolley wire forming a part of an overhead trolley system comprising, an elongated strain member, an elongated curved member with means for attachment to the trolley wire at spaced points, means on the said curved member adjacent its longitudinal center cooperating with means on the strain member to secure the curved member to the strain means member with their longitudinal axes substantially at right angles and whereby the point of attachment of the central portion of the curved member may be moved longitudinally of the strain member to effect a change in the curvature of the curved member, means associated with the device to receive the trolley wire intermediate its points of attachment to the curved member and means associated with the strain member to receive supporting means for the support.

15. A flexible support for a trolley wire forming a part of an overhead trolley system, comprising an elongated strain plate provided with means for attaching supporting means thereto, an elongated curved bar of bendable material, means at each end of the bar to receive and hold the trolley wire in predetermined relation to the bar, means intermediate the ends of the bar for securing the bar to the plate, means associated with the plate to receive and grip the trolley wire intermediate its points of attachment to the ends of the bar, the last two means being spaced apart along the longitudinal axis of the plate and one of the last two said means being adjustable along the longitudinal axis of the plate whereby the curvature of the bar may be varied and the ends of the bar brought into tangency with the trolley wire.

16. A flexible construction for a pair of trolley wires in an overhead trolley system comprising, a pair of plate-like devices, a pair of flexible curved members subject to curvature change having running surfaces along the lower edges thereof, means securing the devices and flexible curved members in fixed relation, insulating means for holding the said devices in spaced and insulated relation, means for attaching the trolley wires to the devices and to the flexible members, each device provided with means whereby the point of attachment of the flexible member thereto may be varied and thereby alter the curvature of the flexible members to bring the ends into tangency with their respective trolley wires.

17. A strain plate for use with a trolley wire

forming part of a curve of an overhead trolley system comprising, an elongated member, means on the member to receive supporting means therefor, means on the member to receive the trolley wire and elongated means extending longitudinally of the member substantially along its longitudinal center line and opening through the

member to receive attaching means on an adjustable curved bar whereby the position of the bar may be changed longitudinally of the member to change the curvature of the bar and bring the ends thereof into alignment with the trolley wire.

SAMUEL S. MATTHES.
